INVENTOR.

UNITED STATES PATENT OFFICE.

MICHAEL F. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

SHOE.

Application filed January 12, 1924. Serial No. 685,924.

This invention relates to improvements in shoes and particularly to the reinforcement of shoe uppers so as to prevent stretching or tearing of the material of the shoe uppers by shoe lacings.

Invisible eyelets, that is to say eyelets inserted in shoe uppers with their flanges positioned upon the lining or facing and with their prongs clenched between adjacent 10 layers so that they cannot be seen upon the outside of the finished shoe, have become very popular in the shoe trade. These are desirable from the point of view of the manufacturer, the retailer and the public 15 generally as a style feature on account of their neat and attractive appearance. They are additionally attractive to the shoe manufacturer on account of the fact that eyelets which are satisfactory for insertion in this 20 way in medium and high grade shoes cost substantially less than the type of eyelet which it is necessary to use in those grades of shoes if the eyelets are set in the ordinary way with their flanges lying upon the upper 25 leather so that they are visible upon the outside of the finished shoe.

It is an object of the present invention to reinforce shoe uppers in a manner which, when a shoe is worn, will give the style 30 effect of invisible eyelets and which will cost even less than invisible eyeleting.

With these objects in view, the shoe upper is provided with reinforcing fastenings inserted therethrough adjacent to the lacing 35 holes and positioned to be covered by the lacings when the shoe is worn. In the illustrated embodiment of the invention, a staple is inserted through the shoe upper adjacent to but somewhat removed from the edge of 40 each lacing hole and positioned relatively to the lacing hole so as to be covered by the shoe lacing when the shoe is worn. Shoes equipped in this fashion, the lacing holes of which are not eyeleted at all, cannot be 45 distinguished on the feet of the wearer from shoes having invisible eyelets. Moreover, it has been found by experience that the uppers of shoes so equipped stand up in a very satisfactory fashion under wear and 50 that the lacing holes do not stretch or tear under the strains to which they are subjected.

With the above and other objects and features in view, the invention will now be described with reference to the accompanying drawings and pointed out in the claims.

In the drawings,

Fig. 1 is a perspective view of a shoe embodying the present invention;

Fig. 2 is a view on an enlarged scale of a portion of the upper of the shoe of Fig. 1;

Fig. 3 is a sectional view on a still larger scale taken on the line 3—3 of Fig. 2; and

Fig. 4 is a front elevation of the portions of the shoe upper adjacent to the lower end of the lacing slit.

The upper of the illustrated shoe is composed of the usual upper leather 6 and lining 8, and, as shown in Figs. 2 and 3, is provided adjacent to the edges of the lacing slit with a reinforcing stay 10. The lacing 70 holes 12 are punched in the usual location to receive the lacing 14. Instead of being eyeleted, the lacing holes of the illustrated shoe are reinforced by staples 16 inserted through the layers of the shoe upper with 75 their bars 18 lying upon the outside of the upper leather, which may be slightly compressed thereby, and with their prongs 20 extending through the layers of the shoe 80 upper and clenched at 22 upon the lining inside the shoe.

In order that the bars of the staples may be completely covered by the shoe lacing, it is helpful to position the staples which reinforce the lower pair of lacing holes (Fig. 85 4) and, if the shoe is not provided with lacing hooks, those which reinforce the upper pair of lacing holes (Fig. 2) so that their bars are bisected by a straight line connecting the two lacing holes of the pair, 90 while the staples which reinforce the other lacing holes (Figs. 2 and 4) are preferably positioned somewhat above that line and at an inclination to it. To show this more clearly, in Fig. 4 the position occupied by 95 the lacing is indicated by broken lines 24, 26. It should be noted, moreover, that by clenching the prongs of the staples away from each other, the shoe upper is reinforced over a distance considerably greater 100 than the length of the bar of the staple.

Having described the invention, what I claim as new and desire to secure by Letters Patent of the United States is:—

1. A shoe having an upper provided with 105 non-eyeleted lacing holes, each lacing hole being reinforced by a fastening passing through the material of the shoe upper at a point removed from but adjacent to the lacing hole and positioned to be covered by 110

the lacing when the shoe is worn.

2. A shoe having an upper provided with lacing holes, the lacing holes being reinforced by staples inserted in the shoe upper in position to be covered by the lacing when the shoe is worn.

3. A shoe having an upper composed of two or more layers of material with a lacing hole punched therein and having a reinforcing staple inserted in the stock of the shoe upper adjacent to the lacing hole and positioned to be covered by the lacing when the shoe is worn.

4. A shoe upper having lacing holes each reinforced by a staple with its bar lying upon the outer surface of the upper leather and its prongs clenched inside the shoe upper the bar of the staple adjacent to the lacing hole and positioned to be covered by the lacing when the shoe is worn.

5. A shoe having an upper provided with lacing holes each reinforced by a staple having its bar lying on the outer surface of the shoe upper in position to be covered by the lacing when the shoe is worn and having its prongs clenched with their clenched portions turned away from each other.

6. A shoe having an upper provided with non-eyeleted lacing holes each reinforced by

a staple having its bar lying upon the outside of the shoe upper in position to be covered by the lacing when the shoe is worn and its prongs clenched in the material of the shoe upper with their clenched ends turned away from each other.

7. A shoe having an upper provided with lacing holes each reinforced by a staple having its bar lying upon the outer surface of the upper leather and its prongs clenched inside the shoe upper, the bars of the staples being adjacent to the respective lacing holes, and the bars of the staples adjacent to the lower pair of lacing holes being bisected by a straight line connecting the lacing holes of the pair.

8. A shoe having an upper provided with lacing holes, each reinforced by a staple having its bar lying upon the outer surface of the upper leather and its prongs clenched inside the shoe upper, the bars of the staples being adjacent to the respective lacing holes, and the bars of some of the staples being somewhat above and at an inclination to a line connecting the lacing holes of a pair.

In testimony whereof I have signed my name to this specification.

MICHAEL F. BROGAN.
